SMOKE DISPOSAL AND DRAFT INDUCING APPARATUS FOR LOCOMOTIVES

Harry G. Day and William E. Skinner, Minneapolis, Minn.; said Skinner, deceased, assignor by decree of court to Eleanor Caywood Skinner

Application June 3, 1940, Serial No. 338,568

15 Claims. (Cl. 104—52)

This invention relates to a smoke disposal and draft inducing apparatus for locomotives of the type utilized in round houses for conducting the products of combustion from the stacks of, and for inducing draft in the furnaces of, locomotives.

An object of the invention is to provide an apparatus of the character mentioned wherein will be incorporated various novel and improved features and characteristics of construction designed to render the present apparatus an improvement generally over more or less similar apparatuses heretofore known.

Further objects are to provide in the apparatus a novel and improved construction and arrangement for associating or assembling an uptake pipe or conduit of the apparatus with, and for removing said uptake pipe or conduit from, the smoke stack of a locomotive; to equip the apparatus with a novel and improved raising and lowering mechanism adapted to be actuated to associate or assemble an uptake pipe or conduit of the apparatus with, and to remove said uptake pipe or conduit from, the smoke stack of a locomotive; to equip the apparatus with a novel and improved swinging apparatus adapted to be actuated to cause the lower portion of an uptake pipe or conduit of the apparatus to be brought into substantially vertical alignment with the smoke stack of a locomotive; to provide in the apparatus a novel and improved construction and arrangement for raising and lowering and swinging an uptake pipe or conduit of the apparatus adapted to permit a locomotive smoke stack to be in communication with said uptake pipe or conduit at variable locations in the vicinity of said apparatus; to provide in the apparatus a novel and improved construction and arrangement for actuating an uptake pipe or conduit of said apparatus to, and releasably retaining said uptake pipe or conduit in, an elevated, inoperative position; and to provide in the apparatus a novel and improved construction and arrangement for controlling a cover for an uptake pipe or conduit of said apparatus in such manner that said cover can be retained in open or in closed condition of said uptake pipe or conduit.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes

in details of construction and arrangement of parts being permissible so long as within the spirit of the invention and the scope of the claims which follow.

5 In the accompanying drawings forming a part of this specification,

Fig. 1 is an elevational view of an apparatus in which the features and characteristics of the invention are incorporated;

10 Fig. 2 is an enlarged horizontal sectional view, taken on line 2—2 in Fig. 1;

Fig. 3 is an enlarged fragmentary longitudinal sectional view detailing any one of several different cylinder-with-piston devices of the apparatus;

15 Fig. 4 is an enlarged elevational view detailing mechanism for releasably retaining an uptake pipe or conduit of the apparatus in an elevated, inoperative position;

Fig. 5 is a vertical sectional view, taken on line 5—5 in Fig. 4;

Fig. 6 is a horizontal sectional view, taken on line 6—6 in Fig. 4;

Fig. 7 is an enlarged end elevational view of either one of a pair of substantially duplicate multiple-valve units of the apparatus;

Fig. 8 is a side elevational view of the multiple-valve unit disclosed in Fig. 7;

Fig. 9 is a detail sectional view, taken on line 9—9 in Fig. 8, of the multiple-valve unit disclosed in Figs. 7 and 8;

Fig. 10 is a fragmentary elevational view of an apparatus generally like the apparatus illustrated in Fig. 1, but including mechanism of modified construction for releasably retaining an uptake pipe or conduit of said apparatus in an elevated, inoperative position;

Fig. 11 is an enlarged horizontal sectional view, taken on line 11—11 in Fig. 10, detailing features of the modified mechanism for releasably retaining an uptake pipe or conduit of the apparatus in an elevated, inoperative position;

Fig. 12 is a vertical sectional view, taken as on line 12—12 in Fig. 11, further detailing said modified mechanism; and

Fig. 13 is a still further detail sectional view, taken as on line 13—13 in Fig. 12, of the modified uptake pipe or conduit releasably retaining mechanism.

With respect to the drawings and the numerals of reference thereon, 15 designates the roof of a round house which may have engine stalls in any desired number, and 16 represents the smoke stack of a locomotive upon a track

(not shown) upon the round house floor and within a stall of said round house.

A separate smoke disposal and draft inducing apparatus, denoted generally at 17, may be provided for each stall.

An uptake pipe or conduit 18 of the apparatus 17 may consist of an upper barrel 19, suitably and conveniently supported upon the round house roof in an opening thereof and having its lower end portion disposed in an upper part of the round house, an intermediate barrel 20 having its upper end portion pivotally supported, as at 21, upon the lower end portion of the upper barrel 19, and a lower barrel 22 having its upper end portion telescopingly received, as at 23, in the lower end portion of the intermediate barrel 20.

The pivotal arrangement between the upper barrel 19 and the intermediate barrel 20 is such that said intermediate barrel 20 and the lower barrel 22 can swing as a unit longitudinally of the track supporting a locomotive having the smoke stack 16, and the intermediate barrel 20 desirably will include elongated slots (not shown) in its opposite walls receiving the pivot pin 21 to allow for slight sidewise swinging movement of the intermediate and lower walls, as, for example, to accommodate the lower barrel 22 to a locomotive smoke stack which may not be exactly vertical, as will be understood. The upper end of the intermediate barrel 20 desirably snugly engages the inner wall of the belled lower portion 24 of the upper barrel 19 to provide a slidably, preferably close fit between the barrels 19 and 20 no matter what may be their relative positions.

The apparatus includes mechanism, denoted generally at 25, for raising and lowering the lower barrel 22 by sliding movement of said lower barrel within the intermediate barrel 20, and the telescoping barrels may be suitably and conveniently equipped with mechanism (not shown) adapted to prevent binding which might otherwise be caused were lifting movement upon the telescoping lower barrel 22 in some instance or other unevenly applied.

The raising and lowering mechanism 25 incorporates as a part thereof a pair of different, duplicate, cylinder-with-piston devices, denoted 26 and 27, respectively, one of which is disclosed in detail in Fig. 3 of the drawings.

More explicitly, each cylinder-with-piston device 26 and 27 consists of an elongated cylinder 28 which slidably contains a piston 29 situated at an intermediate portion of the elongated cylinder, and the piston 29 is rigid with a connecting rod, indicated 30 in Fig. 3, slidably guided, as at 31, in one end portion of the cylinder. Also, each elongated cylinder 28 includes an opening 32, one opening being shown in said Fig. 3, adjacent each of its opposite ends. That is, the openings 32 to each cylinder 28 are at opposite sides of the piston 29. The cylinder 28 of each of the cylinder-with-piston devices 26 and 27 has closed opposite ends, numeral 33 representing a packing gland at the location where the connecting rod 30 is guided in the corresponding end of said cylinder 28. Stated differently, each elongated cylinder 28 is closed save for the openings, such as 32, leading into the interior of the cylinder adjacent its opposite end portions. The end of the cylinder 28 of Fig. 3 opposite the end having the packing gland 33 integrally supports a connector 34 at the outer side of said cylinder and aligned with the connecting rod 30, and said

connecting rod extends outwardly beyond the corresponding end of the cylinder.

Said mechanism 25 for raising and lowering the lower barrel 22 also incorporates a multiple-valve unit, represented 35 in Fig. 1, which is one of a pair of substantially duplicate multiple-valve units included as a part of the apparatus and disclosed in detail in Figs. 7, 8 and 9.

More explicitly, the multiple-valve unit of said Figs. 7, 8 and 9 is constituted as a casing 36 enclosing a rotatable compound valve 37. Said casing includes four ports, denoted 38, 39, 40 and 41, respectively, arranged at 90° apart about the casing. The port 38 is for connecting a source of supply (not shown) of fluid, desirably liquid, under pressure with the interior of said casing 36, the ports 39 and 41 are for affording communication between the interior of the valve casing and the upper and lower ends, respectively, of the elongated cylinders 28 of the devices 26 and 27, and the port 40 is for connecting said interior of said valve casing with a container (not shown) for fluid whence the fluid can be again utilized at said source of supply. The ports 38, 40 and 39, 41, respectively, are 180° apart. The compound valve 37 is adapted to be manually rotated selectively to cause the ports 38-39 and 40-41, respectively, to be in communication with each other by way of the interior of the valve casing 36, with separation between the ports 38-41 and 39-40, respectively, or to cause the ports 38-41 and 39-40, respectively, to communicate, with separation between the ports 38-39 and 40-41, respectively. Numeral 42 designates a hand piece rigid with said compound valve 37 through the instrumentality of which the compound valve can be rotated.

A pipe connection 43 leads from the source of supply of fluid under pressure to the port 38 of the multiple-valve unit 35, and a pipe connection 44 leads from the port 40 of said multiple-valve unit 35 to said container for fluid whence the fluid can return to said source of supply. A pipe connection 45 extends between the port 39 of the multiple-valve unit 35 and openings 32 in the upper portions of the elongated cylinders of the devices 26 and 27, and a pipe connection 46 extends between the port 41 of said multiple-valve unit 35 and openings 32 in the lower portions of said elongated cylinders of said devices 26 and 27. The pipe connection 45 includes a normally looped or bent, flexible portion 47 thereof adjacent the uptake pipe or conduit 18 which connects with a bifurcated part 48 of said pipe connection 45 separately leading to the opening 32 adjacent the upper end of the elongated cylinder of each device 26 and 27. The pipe connection 46 includes a normally looped or bent, flexible portion 49 thereof adjacent said uptake pipe or conduit 18 which connects with a part 50 of said pipe connection 46 extending downwardly along the uptake pipe or conduit, and said part 50 connects with a bifurcated part 51 of the pipe connection 46 separately leading to the opening 32 adjacent the lower end of the elongated cylinder of each device 26 and 27. The pipe connections 43, 44, 45 and 46 are of course rigid with the multiple-valve unit 35, and the bifurcated parts 48 and 51 are of course rigid with the cylinder-with-piston devices 26 and 27, as well as rigid with the pipe connections 45 and 46, respectively. The proper relative positions of the parts of said pipe connections 45 and 46

can be insured in any ordinary or preferred manner.

In Figs. 1 and 2 of the drawings the connecting rods 30 of the devices 26 and 27 extend downwardly, and the connectors 34 of said devices 26 and 27 extend upwardly. The lower end of each connecting rod of each device 26, 27 is oscillatably secured, as at 52, for pivotal movement in a vertical plane, to a belled lower portion 53 of the lower barrel 22, and the upper end of each connector of each device 26, 27 is oscillatably secured, as at 54, for pivotal movement in a vertical plane, upon the cross pin 21 which pivotally supports the intermediate barrel 20 upon the upper barrel 19 of the uptake pipe or conduit 18. The devices 26 and 27 are disposed at diametrically opposite sides of the uptake pipe or conduit 18, and the oscillatable connections, at 52, between the connecting rods and the belled lower portion 53 are actually between said connecting rods and a cross pin 55 which pivotally supports a locomotive smoke stack engaging element 56 upon and within said belled lower portion 53. The upper end of said element 56 desirably snugly engages the inner wall of the belled lower portion 53 to provide a slidable, preferably close fit between the lower barrel 22 and the element 56 no matter what may be their relative positions. Said smoke stack engaging element 56 is hollow and includes a flat lower end 57 adapted to be rested upon the upper end of the smoke stack of a locomotive.

The apparatus includes mechanism, denoted generally at 58, for swinging the intermediate and lower barrels 20 and 22 longitudinally of the locomotive having the smoke stack 16 thus to cause the lower barrel 22 to be brought into vertical alignment with said smoke stack so that this can be placed in communication with the uptake pipe or conduit 18 of the apparatus at variable locations in the vicinity of the apparatus.

The swinging mechanism 58 incorporates as a part thereof a cylinder-with-piston device 59 constructed in the manner as described in connection with the disclosure of Fig. 3 of the drawings.

Said mechanism for swinging the intermediate and lower barrels of the uptake pipe or conduit 18 also incorporates a multiple-valve unit 60 which is substantially like the multiple-valve unit described in connection with Figs. 7, 8 and 9.

The pipe connection 43 leads by a branch 61 from the source of supply of fluid under pressure to the port 38 of the multiple-valve unit 60, and the pipe connection 44 leads by a branch 62 from the port 40 of said multiple-valve unit 60 to said container for fluid whence the fluid can return to said source of supply. A pipe connection 63 extends between the port 39 of the multiple-valve unit 60 and an opening 32 in the upper portion of the elongated cylinder of the cylinder-with-piston device 59, and a pipe connection 64 extends between the port 41 of said multiple-valve unit 60 and an opening 32 in the lower portion of said elongated cylinder of said device 59. The pipe connection 63 includes a normally looped or bent, flexible portion 65 thereof adjacent the device 59, and the pipe connection 64 includes a similar flexible portion 66. The flexible portion 65 is connected directly to the opening 32 adjacent the upper end of the elongated cylinder of the device 59, while the flexible portion 66 is connected to a part 67 of the pipe connection 64 which extends downward.

ly along said device 59 and is connected to the opening 32 adjacent the lower end of said elongated cylinder of said device 59. The branches 61 and 62 and the pipe connections 63 and 64 are of course rigid with the multiple-valve unit 60, and said pipe connections 63 and 64 are also rigid with the cylinder-with-piston device 59. The proper relative positions of the parts of the pipe connections 63 and 64 can be insured in any ordinary or preferred manner.

In Fig. 1 of the drawings, the connecting rod, denoted 68, of the device 59 extends downwardly, and the connector, denoted 69, of said device 59 extends upwardly. The connecting rod 68 is equivalent to the connecting rod 30 and the connector 69 is equivalent to the connector 34. The lower end of said connecting rod 68 is oscillatably secured, as at 70, for pivotal movement in a vertical plane, to an annular metal strap 71 surrounding and rigid with the lower end portion of the intermediate barrel 20, and the upper end of the connector 69 is oscillatably secured, as at 72, for pivotal movement in a vertical plane, upon an eye member 73 rigid with the round house roof. The cylinder-with-piston device 59 slants downwardly from the general location of the round house roof to the lower portion of the intermediate barrel 20 of the uptake pipe or conduit 18, and said device 59 is disposed longitudinally of the track which supports the locomotive having the smoke stack 16, directly above said track.

The apparatus includes mechanism, denoted generally at 74, for releasably retaining the lower barrel 22 of the uptake pipe or conduit 18 in an elevated, inoperative position. The mechanism 74 is clearly disclosed in Figs. 1, 2, 4, 5 and 6 of the drawings.

Said mechanism 74 includes a supporting bracket member or stirrup 75 which is rigidly fixed, as by welding or otherwise, to the annular metal strap 71, and a supported bracket member or stirrup 76 which is rigidly secured, as at 77, to an outer, upper surface of the belled lower portion 53 of the lower barrel 22 of the uptake pipe or conduit 18.

The bracket member or stirrup 75 includes a flat, generally rectilinear slab of metal contiguous with the annular metal strap 71 having an integral thickened lower portion 78 providing an upwardly facing, horizontal shoulder 79 adjacent a lower part of an outer surface of said bracket member or stirrup 75. The outer surface of the thickened lower portion 78 is beveled, as indicated at 80, to slant inwardly and downwardly from the outer end or edge of the upwardly facing, horizontal shoulder 79 to the lower end of the bracket member or stirrup 75. Said outer end or edge of said horizontal shoulder 79 is parallel with the outer surface of the upper portion of the slab of metal which said bracket member or stirrup 75 includes, and the beveled surface 80 lies in an oblique plane including the outer end or edge of the horizontal shoulder 79. Oppositely disposed retaining and guiding elements 81 are integral or rigid with the opposite side edges of the bracket member or stirrup 75 and extend in direction longitudinally of said bracket member or stirrup, away from the annular metal strap 71 and toward each other. More explicitly, each retaining and guiding element 81 is constructed to provide an L-shape guideway 82 which is contiguous with the upwardly facing, horizontal shoulder 79 and is disposed partially above and partially below said horizontal shoulder 79.

der at the outer side of the bracket member or stirrup 75, and the guideways 82 are in opposed, facing relation to each other. An upper portion of each retaining and guiding element 81 is constituted as an upwardly extending resilient arm 83 which is rigid with the corresponding retaining and guiding element at its lower portion and is free at its upper portion. The resilient arms 83 are disposed at the side of the bracket member or stirrup 75 opposite the annular metal strap 71 in front of and adjacent opposite side portions of the upper part of the outer surface of said bracket member or stirrup 75. That is, there is a resilient arm 83 directly above each guideway 82. Desirably, the upper or free ends of the resilient arms 83 normally are engaged against the outer surface of the bracket member or stirrup 75, and said resilient arms 83 are smoothly curved and extend outwardly and downwardly.

The bracket member or stirrup 76 is constituted as a vertically disposed, somewhat flexible strip of metal extending upwardly from the belled lower portion 53 of the lower barrel 22 of the uptake pipe or conduit, and the upper end portion of said bracket member or stirrup 76 is bent to provide a downwardly facing, horizontal shoulder 84 at the side of the strip of metal adjacent the thickened portion 78 of the bracket member or stirrup 75 and a beveled surface 85 slanting inwardly and downwardly from the upper end of the bracket member or stirrup 76 to the inner end or edge of the downwardly facing, horizontal shoulder 84. Said inner end or edge of said horizontal shoulder 84 is parallel with the inner surface of the strip of metal which constitutes the bracket member or stirrup 76, and the beveled surface 85 lies in an oblique plane including the inner end or edge of the horizontal shoulder 84. The strip of metal constituting the bracket member or stirrup 76 is at the outer side of and parallel with the slab of metal constituting the base of the bracket member or stirrup 75, and the beveled surfaces 80 and 85 slant downwardly and inwardly at substantially the same angle. The upper portion of the bracket member or stirrup 76 which provides the horizontal shoulder 84 and the beveled surface 85 is of width to be freely received between the spaced apart, oppositely disposed retaining and guiding elements 81 of the bracket member or stirrup 75. A guide pin 86, fixed in a hollow part 87 of the upper portion of said bracket member or stirrup 76, includes opposite end portions 88, 88 of said guide pin disposed in the opposite guideways 82, 82, respectively, when the lower barrel 22 is in elevated, inoperative position.

In Figs. 1, 2, 4, 5 and 6 of the drawings the downwardly facing, horizontal shoulder 84 is disclosed seated upon the upwardly facing, horizontal shoulder 79 to retain the lower barrel 22 in an elevated, inoperative position, as said lower barrel is disclosed in Fig. 1. To release the supported bracket member or stirrup 76 from the supporting bracket member or stirrup 75, so that the lower barrel 22 can be moved to a depressed, operative position, all that is necessary is to elevate said lower barrel within the intermediate barrel 20 from the position of the lower barrel as in said Fig. 1 to position where the opposite end portions 88, 88 of the guide pin 86 ride upwardly beyond the upper, free ends of the resilient arms 83. Clearly, said opposite end portions 88, 88 of said guide pin 86 will cause said resilient arms 83 to be flexed outwardly from the

base of the bracket member or stirrup 75 in response to elevation of the bracket member or stirrup 76, and when the guide pin 86 has moved upwardly to position above the upper ends of the resilient arms 83 these will spring back to their normal positions beneath said guide pin. When the lower barrel 22 is moved downwardly after moved upwardly to situate the opposite end portions 88, 88 of the guide pin 86 clear of the upper, free ends of the resilient arms 83, said opposite end portions 88, 88 will ride down over the outer surfaces of the smoothly curved, outwardly and downwardly extending resilient arms. During such downward movement of the bracket member or stirrup 76 the strip of metal which constitutes said bracket member or stirrup will be flexed outwardly to cause the horizontal shoulder 84 to be clear of the horizontal shoulder 79. The construction and arrangement are such that the opposite end portions 88, 88 of the guide pin 86 will cause the strip of metal of the bracket member or stirrup 76 to be flexed to extent situating said horizontal shoulder 84 clear of said horizontal shoulder 79 until the former has passed downwardly beyond the elevation of the latter. Evidently, when the supported bracket member or stirrup 76 is thus released from the supporting bracket member or stirrup 75 the lower barrel 22 can be depressed or moved downwardly to an operative position. Said bracket member or stirrup 76 will spring back to its normal position when the opposite end portions 88, 88 of the guide pin 86 become released from the lower ends of the outer surfaces of the retaining and guiding elements 81, as will be obvious. To again assemble the supported bracket member or stirrup 76 with the supporting bracket member or stirrup 75, so that the horizontal shoulder 84 will rest upon the horizontal shoulder 79, all that is necessary is to elevate the lower barrel 22 within the intermediate barrel 20 from a lowered or operative position of said lower barrel to the position of the lower barrel as in Fig. 1. Upon such elevation of the lower barrel the beveled surface 85 will slide upwardly over the beveled surface 80 while the bracket member or stirrup 76 becomes flexed outwardly, and when said horizontal shoulder 84 reaches elevation just above said horizontal shoulder 79 the resilient potential of the strip of metal constituting said bracket member or stirrup 76 will cause the shoulders to become interengaged as disclosed in Fig. 5.

In Figs. 10 to 13 of the drawings there is disclosed a modified mechanism, represented generally at 89, for releasably retaining the lower barrel, such as 22, of an uptake pipe or conduit, such as 18, of an apparatus of the present character in an elevated, inoperative position.

Said mechanism 89 includes a supporting entity 90 which is rigidly fixed upon the outer surface of an upper portion of the intermediate barrel 20, and a supported entity 91 which is rigidly fixed upon the outer surface of the upper portion of the lower barrel 22. The supporting entity 90 is at the outer side of the uptake pipe or conduit 18 and the supported entity 91 lies in a space between said intermediate barrel 20 and lower barrel 22. Said supporting entity 90 is at one side of the uptake pipe or conduit 18, and said supported entity 91 as disclosed is in completely surrounding relation to the upper portion of the lower barrel 22.

The supporting entity 90 includes a small, horizontal, closed cylinder 92 extending radially of the intermediate barrel 20. The inner end wall

93 of the cylinder 92 is contiguous with the outer surface of said intermediate barrel and the outer end wall 94 of said cylinder 92 is in somewhat spaced relation to the intermediate barrel. A piston 95 snugly slidably in the cylinder 92 rigidly supports a latch element 96 disposed centrally and longitudinally of said cylinder. The latch element 96 projects from the side of the piston 95 adjacent the uptake pipe or conduit 18, and a portion of said latch element 96 spaced from said piston 95 is slidably guided, at 97, in the inner end wall 93. The inner or free end portion 98 of the latch element 96 extends through an opening 99 in the intermediate barrel 20 and is situated at the interior of said intermediate barrel. The inner or free end of said latch element 96 is constituted as an oblique or beveled surface 100 which extends upwardly and inwardly of the intermediate barrel. A coil spring 101 is situated within the small cylinder 92 at the side of the piston 95 opposite the uptake pipe or conduit 18. One end of said coil spring 101 is seated against said piston 95 and the other end of the coil spring is seated against the outer end wall 94. Normally, said coil spring 101 urges the latch element 96 to position outwardly of the closed cylinder 92 and inwardly of the intermediate barrel 20, about as disclosed in Figs. 11 and 12 of the drawings. A relatively fine opening 102 extends through the piston 95 at one side thereof and a comparatively larger opening 103 extends through said piston at the opposite side thereof. The fine opening 102 constitutes a passageway through which air can seep or flow slowly in either direction between the chamber 104 of the cylinder 92 at the outer side of the piston 95 and the chamber 105 of said cylinder 92 at the inner side of said piston. The larger opening 103 constitutes a passageway through which air can flow freely from the chamber 104 to the chamber 105. A flap valve 106 within said chamber 105 and normally covering the adjacent end of the larger opening 103 is adapted to preclude passage of air through said opening 103 from the chamber 105 to the chamber 104.

The supported entity 91 is constituted as an annular upper ring 107 fixed about the upper end of the lower barrel 22 and an annular lower ring 108 fixed about the upper end portion of said lower barrel to provide an annular space 109 between said upper and lower rings into which the inner, free end portion 98 of the latch element is adapted to extend. The upper edge portion 110 of the outer surface of the annular upper ring 107 is adapted to be engaged against the oblique or beveled surface 100 constituting the free, inner end of the latch element 96 upon upward movement of the lower barrel 22 to cause said latch element to be pushed outwardly against the resilient action of the coil spring 101, and when said annular upper ring 107 has reached elevation above the latch element, so that said latch element is alined with the annular space 109, said coil spring 101 is adapted to cause the free, inner end portion 98 of the latch element to become seated beneath a downwardly facing, horizontal shoulder 111 which the lower surface of the annular upper ring 107 provides, thus to cause the lower barrel 22 to be retained in an elevated, inoperative position, as it is shown in Fig. 12. The upper edge portion 112 of the outer surface of the annular lower ring 108 also is adapted to be engaged against said oblique or beveled surface 100, upon upward movement of the lower barrel 22 from its position as disclosed in said Fig. 12, 75

to cause the latch element 96 to be pushed outwardly. Desirably, the lower ring 108 is somewhat thicker than the upper ring 107. While the coil spring 101 will return the inner, free end portion 98 of the latch element 96 to its normal, inward position within the intermediate barrel 20, after outward actuation of said latch element, it will be evident that the return action will be slow. The construction and arrangement will be such that upon quick downward movement of the lower barrel 22 from position where the upper edge portion 112 of the outer surface of the annular lower ring 108 is retaining the latch element 96 in position outwardly of the intermediate barrel 20, the downwardly facing, horizontal shoulder 111 will be caused to travel downwardly past the elevation of said latch element 96 before the coil spring 101, limited in its action by the fineness of the opening 102, will have had time to return the latch element to position where it could situate itself beneath said horizontal shoulder 111. In Figs. 11 and 12 of the drawings the downwardly facing, horizontal shoulder 111 is disclosed seated upon the inner, free end portion 98 of the latch element 96 to retain the lower barrel 22 in an elevated, inoperative position, as said lower barrel is disclosed in Fig. 10. To release the supported entity 91 from the supporting entity 90, so that the lower barrel 22 can be moved to a lowered, operative position, all that need be done is to elevate said lower barrel slightly and then move it downwardly quickly. To again assemble the supported entity 91 with the supporting entity 90, so that the horizontal shoulder 111 will rest upon the latch element 96, all that need be done is to elevate the lower barrel from a lowered or operative position to position where the annular space 109 is alined with the latch element 96 and to retain said lower barrel in position where said annular space is in alinement with said latch element for a sufficient, relatively short interval of time to permit the latch element, pushed outwardly by upward movement of the upper ring 107, to become situated within the annular space.

The apparatus includes mechanism for controlling a cover 113 for the upper barrel 19 of the uptake pipe or conduit 18 in such manner that said cover can be retained in the open and in the closed condition of said uptake pipe or conduit. Said cover is adapted to be closed at all times when the apparatus is out of use and is adapted normally to be open when a locomotive smoke stack is situated in operative position relatively to the apparatus. Means is included, however, through the instrumentality of which the cover 113 can be moved to and retained in the closed condition of the uptake pipe or conduit while this is assembled with a locomotive smoke stack.

As disclosed, the cover 113 is pivoted, at the right side of the uptake pipe or conduit in Fig. 1, upon the upper portion of the upper barrel 19 and includes a protruding arm 114 carrying a weight 115 of sufficient magnitude to move said cover to open position. A cord or wire 116 has its upper end attached to the cover 113 at the side of its pivot opposite the weight 115, and its lower end attached, as at 117, to a free end portion of a control lever 118 for said cover. Said control lever 118 is of flat, generally triangular configuration, and is pivotally supported, at location in spaced relation to the cord or wire 116 and adjacent the lower edge of the control lever, upon the cross pin 21. A second cord or wire 119 has its

upper end attached, as at 120, to the control lever 118 at location intermediate the cord or wire 116 and the cross pin 21 and its lower end attached, as at 121, to a free end portion of an actuating lever 122 for the cover 113. Said actuating lever 122 has its intermediate portion pivoted, as at 123, upon the annular metal strap 71, and an end portion 124 of the actuating lever 122, at the side of the pivotal support 123 opposite the cord or wire 119, is situated in angular relation to a vertically disposed actuating element 125 adapted to be engaged with said end portion 124. A lower portion of the actuating element 125 is rigidly secured, as at 126, to the belled lower portion 53 of the lower barrel 22, and the upper end of said actuating element includes a rounded portion, denoted 127, adapted to be slid over the straight, lower edge 128 and the rounded free end 129 of the end portion 124 of the actuating lever 122. The construction and arrangement are such that upon elevation of the lower barrel 22 from a lowered or operative position to the elevated, inoperative position as in Fig. 1, the actuating element 125 engages and swings upwardly the end portion 124 of the actuating lever 122, thus to cause the cord or wire 119, the control lever 118 and the cord or wire 116 to be moved downwardly and the cover 113 to be moved to closed position over the upper barrel 19. As will be apparent, the actuating element 125 is engaged with the free end of the end portion 124 of the actuating lever 122 in Fig. 1 to positively retain the cover 113 in the closed condition of the uptake pipe or conduit 18. At the same time, said actuating element 125 and said actuating lever 122 are relatively arranged so that the actuating element can be moved upwardly from its position as in said Fig. 1, along the free end of the end portion 124, with upward movement of the lower barrel 22 intended to release this from supported relation upon the intermediate barrel 20. Evidently, upon downward movement of said lower barrel 22 after released from said intermediate barrel 20, said actuating element 125 will first slide downwardly along the free end and the lower edge of the end portion 124 and later be removed from engagement with said end portion 124. Upon release of the actuating lever 122 by the actuating element 125, the weight 115 obviously will act to move the cover 113 to open position. That is, said cover 113 normally will be in the open condition of the upper barrel 19 when the lower barrel 22 is in lowered or operative position. The before mentioned means for moving the cover 113 to, and retaining said cover in, the closed condition of the uptake pipe or conduit 18 while this is assembled with a locomotive smoke stack includes a cable 130 ridable over spaced apart pulleys 131. One end of said cable 130 is attached, as at 132, to a portion of the control lever 118 above the cross pin 21, and the other end of the cable is attached, as at 133, to the free end portion of a closing lever 134. Said closing lever 134 is adapted to be pivotally supported, as at 135, upon a fixed part in the roundhouse, and an intermediate part of the closing lever is situated beneath a guide and clamp 136 for said closing lever. Clearly, by swinging the closing lever 134 downwardly the cable 130 is actuated to swing the control lever 118 downwardly thus to move the cover 113 to closed position. The guide and clamp 136 is adapted to stably retain the closing lever 134 at the position in which disclosed in Fig. 1. When said closing lever is swung upwardly the weight 115 causes the cover 113 to be

5 moved to open position unless held closed by the actuating element 125.

An exhauster for the uptake pipe or conduit 18 may consist of a usual or preferred type of fan or blower 137 actuated by a suitable motor 138, both shown situated upon the round house roof. The fan or blower 137 is suitably and conveniently assembled with the upper barrel 19.

Supposing the lower barrel 22 of the uptake pipe or conduit 18 to be in elevated, inoperative position as disclosed in Fig. 1 of the drawings and it is desired to associate a locomotive smoke stack with the element 56 of said uptake pipe or conduit, all that is necessary to be done to accomplish this result is to actuate the compound valve 37 of the multiple-valve unit 60 so that the intermediate barrel 20 and the lower barrel 22 are swung as a unit to position where said element 56 is in vertical alinement with the smoke stack and to actuate the compound valve 37 of the multiple-valve unit 35 so that said lower barrel is moved first upwardly and then downwardly. To return the lower barrel 22 to elevated, inoperative position all that is necessary is to actuate said compound valve 37 of said multiple-valve unit 35 so that said lower barrel is moved upwardly. It will be apparent that the intermediate barrel 20 and the lower barrel 22 can be either vertically disposed, as in full lines in Fig. 1, or obliquely disposed, as in dotted lines in said Fig. 1, when said lower barrel is in elevated, inoperative position.

30 The manner in which fluid under pressure causes the piston 29 to be moved along the cylinder 28, in the instance of each of the cylinder-with-piston devices 26, 27 and 59, will be obvious from the full description hereinbefore made. In the case of each of said devices 26, 27 and 59 the piston 29 is caused to be stationary, when this is intentional, by manipulating the corresponding compound valve 37 to shut off communication between the port 38 and both of the ports 39, 41, as well as to shut off communication between the port 40 and both of said ports 39, 41. This can be accomplished by rotating said corresponding compound valve to position where its oppositely disposed high parts are situated in closing relation to either the oppositely arranged ports 38, 40 or the oppositely arranged ports 39, 41. The compound valve 37 evidently is constructed, in the instance of each of the multiple-valve units 35 and 60, to preclude passage of fluid directly from the port 38 to the port 40, as well as to preclude passage of fluid directly between the ports 39 and 41.

55 The utilization of raising and lowering and swinging mechanism of the character herein presented makes possible the association of an uptake pipe or conduit with a locomotive smoke stack at various locations in the vicinity of a smoke disposal and draft inducing apparatus having said uptake pipe or conduit, and the construction and arrangement as illustrated and described makes provision for variations in the heights of locomotive smoke stacks, as well as for variations from the vertical as may be caused by broken springs.

60 What is claimed is:

1. In an apparatus of the character described, a supporting structure, an uptake conduit including a lower barrel movable relatively to said supporting structure and adapted to be associated with the smoke stack of a locomotive, and fluid pressure actuated means including an element pivotally mounted relatively to said sup-

porting structure, a second element secured to said uptake conduit, a cylinder secured to one of said elements, and a piston reciprocable within said cylinder and secured to the other of said elements for causing said lower barrel to be assembled with and disassembled from said smoke stack.

2. In an apparatus of the character described, a supporting structure, an uptake conduit including an upper barrel upon said supporting structure, a lower barrel adapted to be lowered relatively to said upper barrel to assembled position over a smoke stack of a locomotive and to be raised relatively to said upper barrel to position clear of said smoke stack, and fluid pressure actuated means including an element fixed relatively to said upper barrel, a second element secured to said lower barrel, a cylinder secured to one of said elements, and a piston reciprocable within said cylinder and secured to the other of said elements for lowering and raising said lower barrel.

3. In an apparatus of the character described, a supporting structure, an uptake conduit comprising a plurality of barrels arranged to have upward and downward movement relatively to each other, including a lower barrel adapted to be associated with the smoke stack of a locomotive and an upper barrel with which said lower barrel communicates to carry products of combustion away from said smoke stack, said upper barrel being mounted upon said supporting structure, and fluid pressure actuated means including an element in fixed relation to said upper barrel, a second element secured to said lower barrel, a cylinder secured to one of said elements, and a piston reciprocable within said cylinder and secured to the other of said elements for causing said lower barrel to be lowered to assembled position over said smoke stack and to be raised to an inoperative position.

4. In an apparatus of the character described, a supporting structure, an uptake conduit comprising a plurality of telescoping barrels, including a lower barrel adapted to be lowered to assembled position over the smoke stack of a locomotive and to be raised to an inoperative position and an upper barrel with which said lower barrel communicates to carry products of combustion away from said smoke stack, and fluid pressure actuated means including an element pivotally mounted relatively to said supporting structure, a second element secured to said lower barrel, a cylinder secured to one of said elements, a piston reciprocable within said cylinder and secured to the other of said elements, and means for causing fluid under pressure selectively to be conveyed to the portion of said cylinder at either side of said piston for manipulating said lower barrel.

5. In an apparatus of the character described, a supporting structure, an uptake conduit swingingly mounted upon said supporting structure and including a lower barrel adapted to be associated with the smoke stack of a locomotive, and fluid pressure actuated means including an element pivotally mounted relatively to said supporting structure, a second element pivotally connected to said uptake conduit, a cylinder secured to one of said elements, and a piston reciprocable within said cylinder and secured to the other of said elements for causing said uptake conduit to be swung relatively to said supporting structure to position of substantial vertical alinement with said smoke stack.

6. In an apparatus of the character described, a supporting structure, an uptake conduit mounted upon said supporting structure and including a lower barrel adapted to be moved in direction transversely of the smoke stack of a locomotive and to be associated with said smoke stack, and fluid pressure actuated means including an element pivotally supported in fixed relation to said supporting structure, a second element

10 pivotally secured to said uptake conduit, a cylinder secured to one of said elements, and a piston reciprocable within said cylinder and secured to the other of said elements for causing said uptake conduit to be moved transversely of said smoke stack to position of substantial alinement therewith.

7. In an apparatus of the character described, a supporting structure, an uptake conduit comprising a plurality of barrels including an upper stationary barrel, an intermediate barrel pivotally supported relatively to said upper barrel and a lower barrel supported by said intermediate barrel and adapted to be associated with the smoke stack of a locomotive, and fluid pressure actuated means including an element pivotally mounted upon said supporting structure, an element pivotally mounted upon said intermediate barrel, a cylinder secured to one of said elements, and a piston reciprocable within said cylinder and secured to the other of said elements for moving said intermediate and lower barrels in direction transversely of said upper barrel to cause the lower barrel to be brought into substantially vertical alinement with said smoke stack.

8. In an apparatus of the character described, a supporting structure, an uptake conduit including a sidewise movable lower barrel adapted to be associated with the smoke stack of a locomotive, and fluid pressure actuated means including a rigid element pivotally mounted upon said supporting structure, a rigid element pivotally mounted upon said uptake conduit, a cylinder secured to one of said elements, and a piston reciprocable within said cylinder and secured to the other of said elements for causing said lower barrel to be moved sidewise thus to be brought into substantially vertical alinement with said smoke stack.

9. In an apparatus of the character described, a supporting structure, an uptake conduit including an upper barrel and a lower barrel adapted to be moved in direction transversely of said upper barrel to be brought into substantially vertical alinement with a smoke stack of a locomotive and to be lowered relatively to said upper barrel to assembled position over said smoke stack and raised relatively to said upper barrel to an inoperative position, fluid pressure actuated means including an element pivotally mounted upon said supporting structure, a second element movably connected to said uptake conduit, a cylinder secured to one of said elements, and a piston reciprocable within said cylinder and secured to the other of said elements for causing said uptake conduit to be swung relatively to said supporting structure to position of substantial vertical alinement with said smoke stack, and fluid pressure actuated means including an element substantially fixed relatively to said upper barrel, a second element secured to said lower barrel, a cylinder secured to one of the elements of the last mentioned fluid pressure actuated means, and a piston reciprocable within said last

60 mentioned cylinder and secured to the other of

65

70

75

said elements of said last mentioned fluid pressure actuated means for lowering and raising said lower barrel.

10. In an apparatus of the character described, a supporting structure, an uptake conduit comprising a plurality of barrels arranged to have sidewise and upward and downward relative movement, including a lower barrel adapted to be associated with the smoke stack of a locomotive and an upper barrel with which said lower barrel communicates to carry products of combustion away from said smoke stack, fluid pressure actuated means including an element swingingly mounted upon said supporting structure, a second element movably connected to said uptake conduit, a cylinder secured to one of said elements, and a piston reciprocable within said cylinder and secured to the other of said elements for causing said lower barrel to be brought into substantially vertical alinement with said smoke stack, and fluid pressure actuated means including an element substantially fixed relatively to said upper barrel, a second element secured to said lower barrel, a cylinder secured to one of the elements of the last mentioned fluid pressure actuated means, and a piston reciprocable within said last mentioned cylinder and secured to the other of said elements of said last mentioned fluid pressure actuated means for lowering said lower barrel to assembled position over said smoke stack and for raising said lower barrel to an inoperative position.

11. In an apparatus of the character described, a supporting structure, an uptake conduit comprising a plurality of barrels, including an upper barrel, an intermediate barrel pivotally supported upon said upper barrel and a lower barrel adapted to be associated with the smoke stack of a locomotive, said intermediate and lower barrels being arranged in telescoping relation, fluid pressure actuated means including an element pivotally supported upon said supporting structure, a second element pivotally secured to said intermediate barrel, a cylinder secured to one of said elements, and a piston reciprocable within said cylinder and secured to the other of said elements for moving said intermediate and lower barrels in direction transversely of said upper barrel to cause the lower barrel to be brought into substantially vertical alinement with said smoke stack, and fluid pressure actuated means including an element fixed relatively to said intermediate barrel, a second element secured to said lower barrel, a cylinder secured to one of the elements of the last mentioned fluid pressure actuated means, and a piston reciprocable within said last mentioned cylinder and secured to the other of said elements of said last mentioned fluid pressure actuated means for moving said lower barrel to assembled position over said smoke stack and to an inoperative position.

12. In an apparatus of the character described, a supporting structure, an uptake conduit including a swingable and upwardly and downwardly movable lower barrel adapted to be associated with the smoke stack of a locomotive, fluid pressure actuated means including an element pivotally mounted upon said supporting structure, a second element pivotally secured to said uptake conduit, a cylinder secured to one of said elements, and a piston reciprocable within said cylinder and secured to the other of said elements for swinging said lower barrel into substantially vertical alinement with said smoke

stack, and fluid pressure actuated means including an element fixed relatively to a part of said uptake conduit with respect to which the lower barrel is adapted to have movement, a second element secured to one of the elements of the last mentioned fluid pressure actuated means, and a piston reciprocable within said last mentioned cylinder and secured to the other of said elements of said last mentioned fluid pressure actuated means for accomplishing upward and downward movement of the lower barrel.

13. In an apparatus of the character described, a supporting structure, an uptake conduit including a swingable and upwardly and downwardly movable lower barrel adapted to be associated with the smoke stack of a locomotive, fluid pressure actuated means including an element pivotally mounted upon said supporting structure, a second element pivotally secured to said uptake conduit, a cylinder secured to one of said elements, and a piston reciprocable within said cylinder and secured to the other of said elements for swinging said lower barrel into substantially vertical alinement with said smoke stack, and means for accomplishing upward and downward movement of the lower barrel.

14. In an apparatus of the character described, a supporting structure, an uptake conduit including a swingable and upwardly and downwardly movable lower barrel adapted to be associated with the smoke stack of a locomotive, means for swinging said lower barrel into substantially vertical alinement with said smoke stack, and fluid pressure actuated means including an element fixed relatively to a part of said uptake conduit with respect to which the lower barrel is adapted to have movement, a second element secured to said lower barrel, a cylinder secured to one of said elements, and a piston reciprocable within said cylinder and secured to the other of said elements for accomplishing upward and downward movement of the lower barrel.

15. In an apparatus of the character described, a supporting structure, an uptake conduit mounted upon said supporting structure and including a lower barrel adapted to be moved in direction transversely of and upwardly and downwardly relatively to the smoke stack of a locomotive and to be associated with said smoke stack, fluid pressure actuated means including a rigid element pivotally mounted upon said supporting structure, a second rigid element pivotally secured to said uptake conduit, a cylinder secured to one of said elements, and a piston reciprocable within said cylinder and secured to the other of said elements for causing said uptake conduit to be moved transversely of said smoke stack to position of substantial alinement therewith, and fluid pressure actuated means including an element fixed relatively to a part of said uptake conduit with respect to which the lower barrel is adapted to have movement, a second element secured to said lower barrel, a cylinder secured to one of the elements of the last mentioned fluid pressure actuated means, and a piston reciprocable within said last mentioned cylinder and secured to the other of said elements of said last mentioned fluid pressure actuated means for accomplishing upward and downward movement of the lower barrel.

HARRY G. DAY.
WILLIAM E. SKINNER.
